UNITED STATES PATENT OFFICE.

BENJAMIN LEV, OF CLEVELAND, OHIO, ASSIGNOR TO ECLIPSE RAILWAY SUPPLY CO., OF KANSAS CITY, MISSOURI, A CORPORATION OF DELAWARE.

DETACHABLE CAR-FENDER.

No. 815,923.

Specification of Letters Patent. Patented March 20, 1906.

Application filed July 15, 1904. Renewed August 18, 1905. Serial No. 274,810.

To all whom it may concern:

Be it known that I, BENJAMIN LEV, a citizen of the United States, residing at Cleveland, in the county of Cuyahoga and State of Ohio, have invented certain new and useful Improvements in Detachable Car-Fenders; and I do declare that the following is a full, clear, and exact description of the invention, which will enable others skilled in the art to which it appertains to make and use the same.

My invention relates to improvements in detachable car-fenders; and the invention consists in a construction whereby the fender mechanism can be bodily lifted off or removed from the supporting-hangers while the hangers remain upon the car and the fender proper be carried around from end to end of the car when an interchangeable fender is wanted. Otherwise the fender may be folded back into a substantially vertical position, all as hereinafter fully set forth.

In the accompanying drawings, Figure 1 shows a car with a perspective view of my improved fender mechanism thereon. Fig. 2 is an enlarged elevation of the lower portion of one of the fender-hangers and a sleeve thereon and a section elevation of the adjustable supporting-bracket engaged in said sleeve, and Figs. 3 and 4 represent perspective details of the said sleeve and bracket as hereinafter more fully described.

Referring to the drawings, A represents the car, and B one of the tubular hangers supported from or upon the body of the car, as seen in Fig. 1, and provided each with a split sleeve C, clamped thereon by bolts c, as seen in Fig. 2, and adapted by means of said bolts to be raised and lowered upon said hangers, according as it is desired to support the fender at a higher or lower elevation relatively, the said sleeve being the supporting medium for the fender on the hanger. Different cities and different roads have different regulations as to the elevation at which a fender should run; but as this style of fender is not intended so particularly to pick up objects that are lying upon the car-track it may be arranged to run at a higher level than fenders that have to run lower to perform their functions. At any rate the said sleeve C may be raised or lowered upon the hanger, according to the demands of any given place, and is designed to be fixed in such adjust-

ment and not removed therefrom. The said sleeve is provided on opposite sides with lugs 55 or lateral projections c', extending and adapted to be engaged by the hooks d on the inside of the wall of the detachable bracket-support D for the fender-carrying frame E. The said support has a transverse horizontal tubular bearing d' at its bottom, through which the tubular frame E is supported, as plainly seen in Fig. 1. The side portions of said frame project forward at each side and have the safety-carrier G pivoted between them so as 65 to be free to tilt therein as the service of the carrier requires. Now it is desirable to have fenders conveniently removable to be replaced at the opposite end of the car or for other reasons, and to this end the said 70 bracket-support D is provided with hooks within its side walls d'', adapted to engage over the lugs c', and a horizontal lip d''' lower down in position to engage under or beneath the bottom edge of sleeve C and serve to prevent accidental detachment of the bracket. It follows when it is desired to lift off the fender that disengagement must be made by first swinging the support D outward at its bottom from the hanger so as to get from beneath sleeve C and then lifting it off the lugs c' above. The frame E and carrier can then be lifted off together and after detaching the chains F carry the whole bodily around to the other end of the car.

What I claim is—

1. In car-fenders, a suitable hanger, a sleeve fixed thereon provided with lugs on its outside and a bracket-support hooked upon said lugs from the front, substantially as described.

2. In car-fenders, a suitable hanger and a sleeve adjustably clamped thereon and having lateral projections, in combination with a bracket having hooks engaged upon said projections, inward projections on a plane substantially with the lower portion of said sleeve, substantially as described.

3. In car-fenders, a tubular hanger and a sleeve clamped thereon having projections laterally upon its outside, in combination with a bracket-support suspended upon said projections and provided with a horizontal bearing to engage beneath the said sleeve, substantially as described.

4. In car-fenders, a suitable hanger and

lugs thereon laterally at its lower portion, in combination with a bracket hooked over said lugs and having a substantially barrel-shaped bearing transversely in its lower portion, and 5 a fender-supporting frame engaged through said bearing, substantially as described.

5. In car-fenders, a hanger to support the fender on the car and a sleeve adjustably supported in the lower portion of said hanger

having lateral lugs to support the fender, substantially as described.

In testimony whereof I sign this specification in the presence of two witnesses.

BENJAMIN LEV.
